UNITED STATES PATENT OFFICE.

WILLIS T. HINE, OF WEST MEREDITH, NEW YORK.

WHIFFLETREE-COUPING.

SPECIFICATION forming part of Letters Patent No. 292,012, dated January 15, 1884.

Application filed October 2, 1883. (No model.)

To all whom it may concern:

Be it known that I, WILLIS T. HINE, a citizen of the United States, residing at West Meredith, in the county of Delaware and State 5 of New York, have invented a new and useful Whiffletree-Coupling, of which the following, taken in connection with the annexed drawings and letters of reference marked thereon, is a specification.

10 My invention relates to a novel and useful construction of a clip coupling-plate adapted to be fastened to either the evener or cross-bar of vehicles, and for holding the center bolt of the whiffletree; also, to a novel construction of 15 the whiffletree coupling-plate, and also to certain novel combinations of parts, as will be hereinafter described and specifically claimed.

By my invention the cross-bar and whiffletree are saved from the liability of splitting, 20 a more effective and durable coupling secured, and rattling and change of the whiffletree from a proper position prevented.

In the accompanying drawings, Figure 1 is a vertical central transverse section through a 25 whiffletree, evener, and a coupling of my improved construction. Fig. 2 is a front view of my whiffletree-coupling and portions of a whiffletree and evener to which it is attached; and Fig. 3 is a horizontal section in the line α - α 30 of Fig. 1, looking upward, showing a bottom view of the coupling-plate of the whiffletree and a section of the center bolt, its nut, and the annular bearing portions of clip device of evener and the coupling-plate of the whiffletree.

A represents a whiffletree, B an evener, C a lower clip coupling-plate, and D an upper staying coupling-plate. The lower clip coupling-plate, C, has a circular flat horizontal 35 body portion, c , and an upwardly-projecting cylindrical bearing, c' , with a central hole, c'' , through it, and with a socket, c^3 , shaped to hold a nut, e , on the under side, as shown. The plate C is also formed with clip-extensions c^4 , of ordinary construction, which are connected by a yoke, F, having perforated lugs f , through which latter the screw ends of the clip-extensions c^4 are passed. When the 40 clip-plate C is to be fastened to the evener B, the nut e is inserted into the socket c^3 , the clip-extensions c^4 passed down against the front

and rear of the evener, and the yoke F slipped up over the ends of said extensions and fastened thereon by means of nuts c^5 . The lugs f are provided with flat surfaces f' , which coincide with the shape of the evener, and thus take a very firm hold upon the evener and prevent diagonal displacement of the clamp. The yoke F is also provided with a loop, f^2 , to which a strap or chain may be attached and used for 55 connecting the yoke with the cross-bar of tongue, or with the axle; and when so connected the whiffletree will be prevented from detaching itself and allowing the tongue to drop down if the evener becomes broken. The 60 clip coupling-plate C is also provided with a semicircular upper extension or guard, c^6 , which is formed with the body portion c , and between this extension or guard and the body c the coupling-plate D and the whiffletree are 65 placed.

Upon the cylindrical bearing c' of clip-plate C the upper coupling-plate, D, vibrates. This plate consists of a large horizontal portion, d , having a cylindrical rim, d' , two horizontal arms, d^2 , and two vertical projections, d^3 , which extend up to near the top surface of the whiffletree. The portion d of coupling-plate D rests upon the bearing c' , and the rim d' is snugly fitted around the same. The whiffletree 70 A is placed upon the portion d , between the projections d^3 , and upon the arms d^2 , to which latter it is fastened by means of screws, as shown. A central bearing-plate, G, is shown fastened to the top of the whiffletree, to prevent 75 undue wear between it and the guard c^6 ; but this plate might be dispensed with without departing from my invention, essentially. Through the upper end of the extension or guard c^6 , the plate G, the center of the whiffletree, and the portions c and d of the coupling-plate C, a bolt, E, is passed, its head resting upon the extension or guard c^6 , and its 80 threaded end occupying a place in the socket c^3 , being screwed into the nut e by turning it 85 downward therein.

With my construction of coupling, I avoid 90 weakening the evener, as the bolt E does not pass through it, as in some constructions. I also avoid weakening and splitting the whiffletree and evener by strain and wear against the bolt E, as the said wear and strain come upon 95 100

the bearing portions c' d' of the coupling in such a manner as to prevent the forward canting and rattling noise experienced with whiffletree-couplings of ordinary construction.

5 This construction of bearing admits of a smaller and lighter bolt being used, and thus the whiffletree will have a smaller hole through it, and not be so liable to split, while any tendency to split the whiffletree is counteracted by the laterally staying and binding projections d^3 , and of the evener by the clip-extensions c^4 ; and by having the loop f^2 formed on the yoke F, I avoid the necessity of fastening it directly to the evener by passing a bolt or shank through 15 the wood, and thus weakening it, while such loop serves as a safety device in case of a broken evener.

Prior to my invention means have been devised for keeping the center bolt above the 20 evener, as is instanced in Letters Patent No. 138,701; but my improvement greatly simplifies the means heretofore employed, and at the same time gives great strength to both the whiffletree and evener or cross-bar without the 25 necessity of passing the bolt down through both the whiffletree and evener or cross-bar in the manner shown in Letters Patent No. 255,705.

What I claim as my invention, and desire 30 to secure by Letters Patent, is—

1. The coupling for whiffletrees, comprising the perforated plate D, having horizontal portion c^3 , stay and binding projections d^3 , arms d^2 , and an annular rim, d' , the perforated clip- 35 plate C, having horizontal portion c , cylindrical socketed bearing c' c^3 , screw-threaded clip-extensions c^4 , with nuts c^5 , extension or guard c^6 , yoke F, and bolt E, with nut e, substantially as and for the purpose described.

40 2. A whiffletree coupling-plate, D, having the front and rear staying and binding projections, d^3 , arms d^2 , and an annular socket-rim, d' , in combination with a whiffletree, A, having

a passage through it, through which the coupling-bolt E can be passed, substantially as and 45 for the purpose described.

3. The clip coupling-plate C, formed with front and rear clip-extensions, c^4 , socketed bearing c' c^3 , horizontal portion c , extension bolt staying strap or guard c^6 , evener or cross-bar B, and yoke F, in combination with whiffletree A and the center bolt, E, with nut e on its end, said bolt being passed through the whiffletree and fastened by the single nut e in the socket of plate C above the cross-bar B, 55 substantially as and for the purpose described.

4. The combination of a center bolt, E, having a single fastening-nut, e, on its end above the evener or cross-bar B, and the bearing c' d' of the clip coupling-plate C, and the clip whiffletree coupling-plate D, having nut-socket c^3 , substantially as and for the purpose described.

5. The clip coupling-plate C of the evener or cross-bar, having horizontal portion c , screw-threaded front and rear binding-extensions, c^4 , 65 nut-socket c^3 , and a perforated extension or guard, c^6 , substantially as and for the purpose described.

6. In a whiffletree-coupling, the combination of the center bolt, E, above the evener or cross-bar, the clip coupling-plate C, having a bearing, c , and nut-socket c^3 , and the coupling-plate D, having the bearing portions d d' , substantially as and for the purpose described.

7. The clip coupling-plate C, having a socket, 75 c^3 , provided with a nut, e, and extension or guard c^6 , in combination with the coupling-plate D and the bolt E, passed through the extension or guard c^6 , and entered into the nut e above the evener or cross-bar, substantially as and for the purpose described.
